METHOD OF COATING CANS

John M. Hothersall, Brooklyn, N. Y., assignor to
 American Can Company, New York, N. Y., a
 corporation of New Jersey

Application August 2, 1934, Serial No. 738,154

2 Claims. (Cl. 91—68)

The present invention relates to a method of coating cans and is particularly directed to the flowing of liquid coating material into and out of the cans being coated so that a coating deposit is left on their interior walls.

An object of the present invention is the provision of a method of coating cans by introducing a liquid coating material into the interior of the can which comprises creating a difference of air pressure between the can interior and a connected source of supply and then withdrawing the excess material from the can interior by reversing the air pressure.

Another object of the invention is the provision of a method of coating cans by employing the can interior as a part of a coating chamber and causing the coating material to flow from a source of supply into the chamber so formed and over the desired interior can surface by first creating a pressure greater than atmospheric on the surface of the coating material and then reducing this pressure to below atmospheric to remove the excess material from said can.

Another object is the provision of a method of coating cans by momentarily sealing an open end of a can adjacent a reservoir of liquid coating material and creating a pressure on the surface of the material within the reservoir so that it flows therefrom and into the can interior covering the desired surfaces, then syphoning the excess material back into the reservoir leaving the interior can walls coated.

Numerous other objects and advantages of the invention will be apparent as it is better understood from the following description, which, taken in connection with the accompanying drawing, discloses a preferred embodiment thereof.

Referring to the drawing:

Figures 1 and 2 are sectional views of one form 40 of apparatus for carrying out the method steps of the instant invention, Fig. 1 showing a can in position in the apparatus prior to coating, while Fig. 2 shows the same during coating.

In coating cans according to the method steps 45 of the instant invention a can having a bottom end is clamped in position between supporting members associated with an enclosed tank or reservoir of liquid coating material. The interior of the positioned can forms part of a coating chamber which is in direct communication with the coating material in the tank as by means of passageways and pipes one of the latter being immersed in the coating material in the tank.

A difference of pressure is created between the

can interior which is at atmosphere and the interior of the tank which is effected by the introduction of compressed air into the tank above the coating material. This air pressure forces some of the liquid material from the reservoir 5 and through the pipes and passageways completely filling the positioned can.

The can is vented as the coating material enters, the vent opening being associated with a float valve. The rising liquid passes up and beyond the can and comes into contact with the valve closing it and blocking off the vent.

The compressed air is now cut off from the reservoir and vacuum is drawn on the tank. The principal part of the coating material in the can and 15 in the coating chamber thereupon syphons off through the pipes and passageways and returns to the reservoir. As the level of the material falls the float valve lowers and opens the vent and air again enters bringing the coating chamber to its normal atmospheric pressure. A portion of the coating material adheres to the interior surfaces of the can including the inner surface of its flange and a thin, even coating results.

One form of apparatus for performing the steps of the invention is disclosed in the drawing and comprises a tank 11 having a closed bottom 12 and an open top 13. This constitutes a reservoir for holding a supply of liquid coating material 14. The top of the tank is closed with a cover 15 which is securely held in place by screws 16. A filling aperture in the cover 15 which is closed by a screw plug 17 is provided for replenishing the liquid when exhausted.

A flanged can *a* to be coated is shown as having a bottom end *b* and this is obliquely supported adjacent the tank on a rack 21. The bottom of the can rests on a pad 22 of the rack which is preferably disposed at an angle of approximately 40 30 degrees to the horizontal. A ledge 23 extends up from one side of the pad and engages the side of the can. The rack is mounted on the top of and is carried by a depending rod 24 which is preferably connected to any suitable means (not shown) for raising and lowering the rack and can.

With a can in position on the rack 21, the latter is raised to bring the top flange of the open end of the can into sealing engagement with a 50 hollow head member 26. Head member 26 is formed with a depending flared skirt 27 which extends out and over the top of the can and at an angle corresponding to that of the can top. The skirt near its bottom edge is provided with an 55

internal annular channel 28 which provides a seat for a resilient sealing ring 29. It is this ring that the flange of the can seats against and this forms a seal between the can and the hollow head member. This creates a coating chamber part of which is formed by the can interior, while the head interior constitutes the remaining part.

The upper end of the head member is provided with a vent tube 31 which is adapted to be closed 10 off at times by a ball float valve 32. The ball of the valve is disposed in the skirt of the head adjacent the lower end of the tube and is suspended from inside the tube.

For this purpose the ball hangs from the lower 15 end of a rod 33 which extends up inside the tube and terminates in a widened portion having an elongated slot 34. A pin 35 engages within and extends across the slot and has its ends secured in the side walls of the tube. In suspended position the ball of the valve is below the end of the tube as shown in Fig. 1, this being the open position of the valve.

The head member 26 is preferably supported by the tank cover 15 and may be integrally connected with it by a horizontal bracket web 37. Web 37 is formed with an axial or horizontal passageway 38 which is closed at both ends, one end being blind, the other closed by a setscrew 39. The passageway forms a connection between a 30 short vertical bore 41 formed in the head 26 and a similar vertical bore 42 formed in the cover 15. Both bores 41, 42 are formed transversely of the passageway 38 and are plugged at their upper ends with setscrews 43.

These passageways are utilized in connecting the interior of the coating chamber with the interior of the tank 11 for conveying the coating material into the can. The liquid passes by way of a vertical pipe 45 one end of which is threadedly secured in the lower end of the bore 41. Its opposite end extends down into the angularly positioned can and terminates in an angularly shaped bottom end which reaches into the lowest corner of the can (Fig. 1).

A vertical pipe 47 is located as by a threaded engagement within the lower end of the bore 42 and extends down into the tank 11 and into the coating liquid. This pipe terminates just short of the tank bottom 12. The 50 coating material is caused to flow from the tank by way of the pipe 47, passageway 38 and pipe 45 and into the coating chamber partially comprising the can 2 to be coated, by means of an air pressure applied to the surface of the liquid in the reservoir. Control of the air is effected by a two-way valve 51 threadedly secured at 52 to the top of the cover 15.

One outlet of the valve is by way of a pipe 53 threadedly secured thereto which at its outer 60 end connects with any suitable source of compressed air at a desired pressure. The other outlet of the valve is by way of a threadedly secured pipe 54 the outer end of which may connect with a vacuum pump or the like.

When the valve 51 is turned to open communication between the tank 11 and the pipe 53 (Fig. 2) compressed air at a desired pressure is introduced into the tank above the coating material. This forces the liquid through the pipe 47, the passageway 38, down the pipe 45 and into the can, the vent 31 of the coating chamber being open at such a time.

The can is completely filled and the coating material rises up and into the head member 26 75 and lifts the float valve 32 into vent closing posi-

tion against its seat (Fig. 2). This prevents further flow of the liquid coating material.

The valve 51 on being turned to its alternate position (Fig. 1) cuts off the compressed air from the reservoir and opens the vacuum supply. This 5 effects a reversal of pressure conditions, the pressure in the tank being now reduced to a point lower than atmospheric pressure. Consequently the liquid in the head 26 and can *a* or most of it flows in a reverse direction and is syphoned 10 back into the tank, the receding liquid opening the vent 31 of the coating chamber by the gravitational movement of the valve 32.

The return flow of the material drains the can 15 interior of its contents leaving sufficient coating material adhering to the can surfaces to produce the desired coating. Thus the entire interior surface of the can, including its flange, is covered with a thin, even coat.

It will be understood that gravity may be substituted for vacuum and the vacuum pipe connection 54 may be used as a connection to atmosphere. This requires that the relative positions of the coating chamber and the reservoir be changed so that the level of the liquid in the 25 tank is at all times below the chamber. In such a variation of apparatus the compressed air forces the coating material into the can in the manner described but when the valve 51 is opened to atmosphere gravity produces the same syphoning effect and the excess liquid returns to the 30 reservoir leaving the coated can as before.

It is thought that the invention and many of its attendant advantages will be understood from the foregoing description, and it will be apparent 35 that various changes may be made in the steps of the process described and their order of accomplishment without departing from the spirit and scope of the invention or sacrificing all of its material advantages, the process hereinbefore described being merely a preferred embodiment 40 thereof.

I claim:

1. A method of liquid coating cans which consists in supporting a can in inclined position and 45 clamping the open outwardly flanged end of the can against a cup-shaped head member to create a closed coating chamber defined in part by the interior of the can and also by said head member, the upper end of said head member being normally open to atmosphere and the interior of the can being in communication with a closed tank 50 containing a liquid coating material, introducing a fluid pressure greater than atmosphere to the head space in said closed tank above the coating material and thereby forcing a portion of said liquid into said coating chamber while venting the latter through said head member, the said coating liquid flowing over the entire interior can surface including the outwardly flanged open end 60 thereof and thence into the head member thereabove and acting to close communication with the atmosphere, then withdrawing the excess liquid coating material from said coating chamber and from said can by reducing the fluid pressure 65 in the head space of said tank to below atmospheric pressure, the withdrawal of said excess coating material from said chamber restoring atmospheric communication thereof through said head member.

2. A method of liquid coating cans which consists in supporting a can in inclined position and 70 clamping the open outwardly flanged end thereof against a cup-shaped head member to create a coating chamber defined in part by the interior 75

of the can and also by said head member, the upper end of said head member being normally open to atmosphere, the interior of the can and head member being in communication with a closed tank of liquid coating material, introducing a fluid pressure greater than atmosphere to the head space of said tank above the coating material therein to thereby force a portion of said liquid into said coating chamber the while venting the latter, said coating liquid flowing over the entire interior can surface including the outwardly flanged open end thereof and thence into the interior of said head member, closing off said

atmospheric communication by means of the rising liquid to insure complete filling of said coating chamber to completely coat the interior of the can and its flange, and then withdrawing a large part of the liquid coating from said coating chamber and from said can and leaving upon the interior walls of the latter a coating film, this withdrawing action being produced by reducing the fluid pressure in the head space of said tank to below atmospheric pressure, the while again restoring communication of said coating chamber with the atmosphere. 5
